UNITED STATES PATENT OFFICE.

WILLIAM I. BALLENTINE, OF LA PORTE, INDIANA, ASSIGNOR TO ADVANCE-RUMELY COMPANY, OF LA PORTE, INDIANA, A CORPORATION OF INDIANA.

RADIATOR.

Application filed April 12, 1922. Serial No. 552,026.

This invention relates to a radiator for use in connection with an internal combustion engine to cool the cooling medium of the same. It has for one object to provide a 5 radiator in which the area of the surface of radiation is very large in proportion to the total size of the radiator. Another object is to provide a radiator of extreme simplicity and consequent cheapness of construction. 10 Other objects will appear from time to time throughout the specification and claims.

My invention is illustrated more or less diagrammatically in the accompanying drawings, wherein:

15 Figure 1 is a plan view of an element of the radiator;

Fig. 2 is a side elevation of such element;

Fig. 3 is a section taken on line 3—3 of Figure 1 on an enlarged scale;

20 Fig. 4 is a diagrammatic illustration showing a radiator made up of the radiator elements illustrated in the previous figures.

Figure 5 is a partial vertical cross section taken on line 5—5 of Figure 4;

25 Figure 6 is a partial side elevation of the pipe D.

Like parts are designated by like characters throughout.

The radiator is built up of a plurality of 30 elements, one of which is illustrated herewith. Each of the elements is made from two sheets A A of sheet metal. They are fastened together preferably at their outside edges A' by being crimped together and soldered, although they might be secured to- 35

gether in any other suitable manner. Each of the sheets of the radiator elements is stamped out in the form shown particularly in Figure 1 so that when a pair of them is 40 secured together they will produce an extremely long and tortuous passage through which the liquid must flow in passing through the elements. This passage is formed by the outwardly pressed portions

45 A² A² within which lie the engaging portions A³ A³. Along these engaging portions at considerable intervals are positioned rivets A⁴ A⁴ which serve to hold the sheets together.

50 Each of the radiator elements is provided with two connection members B B. In Fig-

ure 3 a section of one of these members is shown on an enlarged scale. Adjacent each of the members the sheets A A are outwardly flared as at B'. The member B is cylindrical in section and is provided with a plurality of ports B² B². These ports communicate with the interior of the member B and with the interior of the radiator section and permit the flow of liquid to and from the section. On one side the member B is provided with the outwardly extending flange B³. The outside diameter of this flange is the same as the inner diameter of the opening B⁴ of the member B. By means of this construction any suitable number of radiator elements can be nested together, and in each case the member B will mate with the corresponding member and a complete tubular connection between all of the radiator 60 elements is thus built up from the individual sections which first form part of each radiator section.

As shown in Figure 4 the radiator elements are assembled to form a complete radiator. The supply pipe C by means of the union C' is connected to the upper connection member of the radiator elements as assembled. The elements as shown are held together by the tying bolt C² which has the 65 enlarged head C³ and the nut C⁴. Through the supply pipe C liquid enters the upper edges of the radiator elements and through the ports in their connections passes down and about the passages in each of the ele- 70

ments.

At the lower end of the radiator a pipe D is inserted. This pipe is of less diameter than the interior of the connection holes in each of the radiator elements and it is per- 75

forated only adjacent one end as at D'. Within the pipe there is positioned a tying bolt E which is similar to the bolt C² above, and it is also provided with an enlarged head E' and a nut E². In communication 80 with the pipe D is a union F which in turn is connected to a discharge pipe F'. By means of the arrangement shown the fluid enters from the supply pipe and some fluid 85 passes through each of the radiator elements gradually coming to its lower edge and thus 90

into the built-up pipe formed of the connec- 95

tion members in each of the radiator elements. Since, however, a pipe lies within these elements and since this pipe is perforated only adjacent the outer end, the fluid must all pass to that end before it can enter the perforation, pass backward through the interior of the pipe and so out through the discharge pipe. Thus the fluid is compelled to circulate through the radiator in a more complete and perfect fashion than would be the case if the additional pipe at the bottom were lacking or if this pipe were perforated throughout its length.

G is a casing surrounding the radiator and provided with an open bottom G¹ and a top stack G² shaped generally in the form of a venturi.

Although I have shown this radiator as being built up from sheet pieces out of which the elements are stamped, it will be obvious that this construction might be departed from, and although I have shown the edges of the sheets as being curled and crimped together, it will also be obvious that they might be soldered or welded and that welding might be substituted for rivets in the interior of the passage without departing from the spirit of my invention. Thus therefore although I have shown an operative form of my invention, still it is obvious that many changes both in form, shape and arrangement of parts might be made without departing from the spirit of my invention.

The use and operation of my invention are as follows:

The sides of the radiator elements are pressed or stamped. They are then assembled in mating pairs with the connection elements secured as shown in the drawings. The radiator proper is then made from a plurality of these sections which are fastened together as shown in Figure 4.

I claim:

1. A cooling radiator composed of a plurality of hollow sections each of said sections provided with a plurality of perforated spacing rings, said rings having laterally extending flanges and being each adapted to mate with the ring of an adjacent section, the flange of each ring adapted to penetrate within the opening of such adjacent ring and thus to form a built-up pipe connecting such sections, an inlet pipe connected to one of said built-up pipes and a discharge pipe connected to another, said discharge pipe being smaller in diameter than and lying within said second built-up pipe and being closed to said pipe throughout a portion of its length, and being perforated through a portion of its length within that portion of the radiator farthest from the discharge opening.

2. A cooling radiator composed of a plurality of hollow sections formed of a pair of stamped metallic sheets and adapted

when joined to form a tortuous closed passage of varying cross sectional area, each of said sections provided with a plurality of perforated spacing rings, said rings having laterally extending flanges and being each adapted to mate with the ring of an adjacent section, the flange of each ring adapted to penetrate within the opening of such adjacent ring and thus to form a built-up pipe connecting such sections, an inlet pipe connected to one of said built-up pipes and a discharge pipe connected to another, said discharge pipe being smaller in diameter than and lying within said second built-up pipe and being closed to said pipe throughout a portion of its length, and being perforated throughout a portion of its length within that portion of the radiator farthest from the discharge opening.

3. A cooling radiator composed of a plurality of hollow sections, each of said sections formed of a pair of metallic sheets, said sheets having laterally bent portions and inwardly extending unbent plain portions, the unbent portions of a pair of mating sheets adapted to contact with each other and to be secured together and to form thereby a tortuous passage of varying cross sectional area through the radiator section, each of said sections provided with a plurality of perforated spacing rings, said rings having laterally extending flanges and being each adapted to mate with the ring of an adjacent section, the flange of each ring adapted to penetrate within the opening of such adjacent ring and thus to form a built-up pipe connecting such sections, an inlet pipe connected to one of said built-up pipes and a discharge pipe connected to another, said discharge pipe being smaller in diameter than and lying within said second built-up pipe and being closed to said pipe throughout a portion of its length, and being perforated throughout a portion of its length within that portion of the radiator farthest from the discharge opening.

4. A cooling radiator composed of a plurality of hollow sections and a plurality of circulation pipes connecting such sections each to the other, a supply connection to one end of one of said pipes and means for causing the cooling fluid to circulate through all of said sections, said means comprising a discharge connection lying within one of said circulation pipes and open to it only at the end opposite to the supply connection.

5. A cooling radiator composed of a plurality of hollow sections each of said sections provided with a plurality of perforated spacing rings, said rings having laterally extending flanges and being each adapted to mate with the ring of an adjacent section, the flange of each ring adapted to penetrate within the opening of such adjacent ring and thus to form a built-up pipe connecting

such sections, an inlet pipe connected to the end of one of said built-up pipes and a discharge pipe connected to another, said discharge pipe being smaller in diameter than and lying within and out of contact with said second built-up pipe, said discharge pipe providing means for causing the cooling

fluid to circulate through substantially all of said radiator sections before it is discharged.

Signed at La Porte, county of La Porte and State of Indiana, this 6th day of April, 1922.

WILLIAM I. BALLENTINE.
